CLAIM

The ornamental design for a towel with aperture and two pouches, as shown and described.

DESCRIPTION

FIG. 1 is a top plan view illustrating a towel with aperture and two pouches embodying my new design, with each pouch including an elastic portion;

FIG. 2 is a bottom plan view illustrating a towel with aperture and two pouches embodying my new design;

FIG. 3 is a front elevation view illustrating a towel with aperture and two pouches embodying my new design, as worn by a user, with a hand of a user inserted in each of the two pouches, with each hand in a raised position and showing an elastic portion of each pouch; and,

FIG. 4 is a rear elevation view illustrating a towel with aperture and two pouches embodying my new design. The broken line outline of the partial human figure in FIGS. 3 and 4 assist in illustrating how the claimed design may appear when in a position of use, but forms no part of the claimed design.
